HAIR WAVING DEVICE

Primo Di-Guango and Vicente Vito,
Manila, P. I.

Application March 9, 1934, Serial No. 714,873

4 Claims. (Cl. 132—31)

This invention relates to hair waving one object of the invention being to provide a hair waving device which is inexpensive, very easy to operate, and by means of which hair can be waved by a person not having special training without danger of injuring the hair.

Another object of the invention is to provide a setting iron which is very simple in construction, and can be easily held in a person's hand 10 and engaged about hair to be set and in addition so form the iron that it may be secured about a lock of hair and suspended from an overhead support during the heating operation.

Another object of the invention is to provide an 15 iron which may be heated by a gas flame or other suitable source of heat, thereby permitting the device to be used in places where electricity is not available.

Still another object of the invention resides in 20 providing a construction which is simple and durable, inexpensive to manufacture and one which will be very efficient in use.

With these and numerous other objects in 25 view, our invention consists in the novel features of construction, combination and arrangement of parts as will be hereinafter referred to and more particularly pointed out in the specification and claims.

The invention is illustrated in the accompanying 30 drawings wherein:—

Figure 1 is a view in side elevation showing the improved waving device in use and suspended from an overhead support.

Figure 2 is a plan view of one of the sections 35 forming the setting iron.

Figure 3 is a sectional view taken longitudinally through the setting iron in use.

Figure 4 is a sectional view taken along the line 40 4—4 of Figure 3.

Figure 5 is a view of a shielding disk used to 45 protect the scalp when the device is in use.

Figure 6 is a sectional view taken along the line 50 6—6 of Figure 1.

Figure 7 is a sectional view taken along the line 55 7—7 of Figure 1.

When waving hair in accordance with this invention a lock of hair is wrapped about a core or shaper which may be referred to as a roller and is then wrapped in cotton saturated 50 with a concentrated solution of potassium bicarbonate. The wrapped lock is then encased in a sheet of lead foil and disposed within a cylindrical heating iron where it remains until the chemical is driven off by the heat of the iron, 55 ends of the iron being open in order that steam

may escape. Only from five to twelve minutes is required to set the hair and the curl will remain in the hair until it disappears as the hair grows and ends are cut off. The setting iron is about the size of a curling iron of a conventional construction and may be easily applied by hand and so held during the setting operation or it may be suspended by a cord from an overhead support as it is light in weight.

The setting iron is somewhat similar in construction to a curling iron and consists of companion sections or members 1 each having at its forward end a blade from which extends a shank 2 carrying a handle 3 at its rear end. The shanks extend in crossed relation to each other and are 10 pivotally connected by a pin or stud 4 and by referring to Figure 1 it will be readily understood that when the handles are grasped the shanks can be rocked about the pivot and the blades moved towards or away from each other according to the direction in which the handles are moved. The blades are each in the form of a trough shaped body arcuate in cross section and by referring to Figures 3 and 4 it will be seen that when the blades are in a closed position with their side edge faces 5 contacting they form a tubular heating chamber 6 which is circular in cross section and open at its ends to permit steam generated during a setting operation to readily escape. A latch 7 is pivoted to the shank 10 of one member as shown at 8 and this latch is in the form of a hook having a bill 9 to engage over a prong or keeper 10 carried by the shank of the other member when the blades are closed and the latch moved to the position shown in 20 Figure 1 in which it extends transversely of the shanks 2 with the keeper wedged between the bill and shank of the latch. A hook 11 extends transversely from the shank carrying the keeper and to this hook may be tied a cord 12 by 30 means of which the setting iron is to be suspended from an overhead support. It will thus be seen that the setting iron may be easily applied to a curled lock of hair and secured after which it may be held in a person's hand or suspended 35 from an overhead support during a setting operation. Protectors 13 each of which consists of an asbestos disk formed with a center opening 14 and a radially extending slit 15 are applied about the lock of hair near the front end of the 40 setting iron in order to prevent a person's scalp from being scalded by hot steam escaping at the front of the chamber 6.

When hair is to be crimped, a lock is wrapped about a core in the form of a metal roller 16 of 45

less length than the chamber 6 and after the hair has been wrapped tightly about the roller a sheet of cotton batting 17 is folded about the hair and extends entirely about the hair for full length thereof. Before being wrapped about the hair the cotton pad or sheet is dipped in a concentrated solution of potassium bicarbonate and after the moistened cotton is in place it is covered by a sheet of lead foil 18 wrapped tightly about 5 the cotton and entirely enclosing it. This lead foil serves as a shield to prevent scorching the cotton or hair and retains heat generated when the blades 1 are closed about the hair and cotton and heat of the iron converts the chemical into 10 steam. The chemical consists of the following ingredients in approximately the proportions set forth.

20 Potassii bicarbonas 145.60 gm.
Methylthioninae chloridum 0.0005 mg.
Spirit of canangium odoratum VI drops
Aquaee distillatae 430 cc.

The pads or cotton sheets are of approximately 1/8 inch thick and each is soaked with 5 cc of the 25 chemical solution either individually or a number saturated at one time in the proper quantity of solution.

After the iron has been applied it is allowed to 30 remain in place from 5 to 12 minutes according to the curl which it is desired to impart to the hair and the iron and pad then removed and the lock of hair uncoiled from the roller. Other locks are treated in the same manner and when all have 35 been curled the hair is washed with soap and tepid water and the curled locks set in place about the head in the usual manner.

We have therefore provided an improved setting iron which is easy to operate and can be 40 readily held in a person's hand while being applied to the hair and securely held in place about the hair. We have further provided a setting iron which when in place can be held in a person's hand during a setting operation or suspended from an overhead support by a cord tied to a 45 portion of the iron.

From the foregoing description of the construction of our improved apparatus, the application of the same to use will be readily understood. It 50 will be seen that we have provided a simple, inexpensive and efficient setting iron.

While we have particularly described the elements best adapted to perform the function set forth, it is obvious that various changes in form, proportion and in the minor details of construction 55 may be resorted to without departing from the spirit or sacrificing any of the principles of the invention.

Having thus described the invention what is claimed is:—

60 1. An iron for setting curled hair comprising companion sections each having a blade and a shank extending rearwardly from the rear end

thereof the shanks being pivotally connected in spaced relation to the blades whereby the blades may be swung towards and away from each other into and out of a closed position and form a cylindrical hair receiving chamber when closed, releasable means for holding the jaws closed, one shank being provided with means whereby the iron may be suspended from an overhead support when in use.

2. An iron for setting curled hair comprising 10 companion sections each having a blade and a shank extending rearwardly from the rear end thereof the shanks being pivotally connected in spaced relation to the blades whereby the blades may be swung towards and away from each other into and out of a closed position and form a cylindrical hair receiving chamber when closed, releasable means for holding the shanks against movement in a direction to open the jaws, and a hook carried by one shank in front of the pivotal 15 connection for the shanks whereby a cord may be tied to the hook and the iron suspended from an overhead support.

3. An iron for setting curled hair comprising 20 companion sections each having a blade and a shank extending rearwardly from the rear end thereof the shanks being pivotally connected in spaced relation to the blades whereby the blades may be swung towards and away from each other into and out of a closed position, and form a 25 cylindrical hair receiving chamber when closed, one shank being provided with a keeper and the other shank carrying a latch movable into and out of engagement with the keeper to retain the blades closed, and means for suspending the curling 30 iron from a flexible overhead support.

4. An iron for setting curled hair comprising 35 companion sections each having a blade and a shank extending rearwardly from the rear end thereof the shanks being pivotally connected in spaced relation to the blades whereby the blades may be swung towards and away from each other, into and out of a closed position, and form a cylindrical hair receiving chamber when closed, one shank being provided with a keeper in the form 40 of a finger extending longitudinally of the shank in spaced relation thereto, a latch carried by the other shank and consisting of a hook pivoted to the shank for swinging movement longitudinally of the shank and having a bill adjacent its free end extending towards the pivoted end of the hook, the latch when moved to an operative position extending transversely of the finger between the finger and the shank carrying the finger with said finger wedged between the bill and hook to 45 prevent movement of the two shanks away from each other and retain the blades closed, and means for suspending the curling iron from a cord carried by an overhead support.

60 PRIMO DI-GUANGCO.
VICENTE VITO.
